UNITED STATES PATENT OFFICE.

JOHN E. GOLDEN, OF MINNEAPOLIS, MINNESOTA.

LIFTING DEVICE.

1,150,671.

Specification of Letters Patent.

Patented Aug. 17, 1915.

Application filed November 14, 1914. Serial No. 872,207.

To all whom it may concern:

Be it known that I, JOHN E. GOLDEN, a citizen of the United States, residing at Minneapolis, in the county of Hennepin and 5 State of Minnesota, have invented certain new and useful Improvements in Lifting Devices; and I do hereby declare the following to be a full, clear, and exact description of the invention, such as will enable others 10 skilled in the art to which it appertains to make and use the same.

This invention relates to improvements in lifting devices or grappling tongs that are designed to grapple ice, stone and other objects.

An object of importance is to provide a device of the character described that is of 20 extremely simple construction, is light, strong and durable, constructed so that it may be readily taken apart for the purpose of repair or renewal of parts which may have become worn or broken and which is 25 permitted a wide range of adjustment and adapted for use in connection with large objects.

The above and additional objects are accomplished by such means as are illustrated in the accompanying drawings, described in the following specification and then more 30 particularly pointed out in the claims.

With reference to the drawings, wherein I have illustrated the preferred embodiment of my invention as it is reduced to practice, and throughout the several views of which 35 similar reference numerals designate corresponding parts—

Figure 1 is a front elevation of my improved lifting device, Fig. 2 is a bottom plan view, Fig. 3 is a fragmentary vertical sectional view taken through the hub member of the device, Fig. 4 is a horizontal sectional view taken in line 4—4 of Fig. 3, and Fig. 5 is an enlarged detail perspective view of the operating links and rod, showing them 45 connected.

Referring to the drawings by characters of reference, the numeral 1 designates as an 50 entirety a cylindrical centrally apertured hub member in which is slidably mounted an operating rod 2. The operating rod 2 is provided at its upper end with a loosely mounted or swiveled attaching ring 3 and is formed with an enlarged annular head 4 on its lower end. The lower part of the 55 aperture in the hub 1 is enlarged, as at 5, to receive said head 4 and permits the rod 2

to move up and down relative to the hub 1. The lower part of the hub 1 is provided with vertical and longitudinal recesses 6. A plurality of these recesses 6 are provided.

Pivotedly mounted within each of the recesses 6 is a grappling hook 7. Preferably three of these hooks are used. Pivot pins 8 are inserted transversely through the hub member 1, through the recesses 6 therein and the upper ends of the shanks of the hooks 7, as clearly shown in Fig. 4. In inner ends 35 of the hooks 7 are spaced sufficiently to enable the head 4 to move freely up and down relative to the member 1.

A screw eye or similar attaching device 9 is secured to the head 4 on the rod 2 and pivotedly secured to the screw eye or like member 9 are operating rods 10. The operating rods 10 are formed with eyes 11 on 75 their free ends and said eyes are connected with eyes 12 carried upon the inner faces of the shank of the hook members 7 at points adjacent the upper ends of said hook members shanks. The operating rods 10 are arranged so as to not interfere with the object being dragged or lifted by the device.

In the use of my device, the ring 3 is connected with a derrick or pull cable of any suitable character, not shown, and upon 85 the relaxation of the cable not shown, the hooks 7 are free to be spread apart as shown in Fig. 1, to effect a grasping or grappling of a stone, block of ice or other object to be dragged or lifted. After the hooks 7 have 90 been arranged about the object to be grasped or lifted, a pull is communicated to the rod 2 which causes the hooks 7 to grapple the object and securely hold it against falling or release therefrom.

As a means for holding the hooks inwardly relative to one another and in fixed position, I provide a slidable ring 13 which is slidable upon the hub member 1 and arranged to be moved downwardly toward the 100 lower end of the hub so as to hold the hooks against outward movement. When the device is used as a drag the ring is downwardly upon the hub so as to hold the hooks in the position above named.

With reference to the foregoing description and accompanying drawings, it will be observed that I have provided an extremely simple and effective hook device, while the hook members are arranged to grasp an 110 object to be dragged or lifted in a reliable manner so that falling thereof is prevented.

In practice, I have found that the form of my invention, illustrated in the drawings and referred to in the above description, as the preferred embodiment, is the most efficient 5 and practical; yet realizing that the conditions concurrent with the adoption of my device will necessarily vary, I desire to emphasize the fact that various minor changes 10 in the details of construction, proportion and arrangement of parts may be resorted to, when required, without sacrificing any of the advantages of my invention, as set forth.

What is claimed is:—

- 15 1. A grappling device comprising a hub having a central bore and a plurality of vertical and longitudinal slots, said bore being enlarged at its lower end, an operating rod slidably mounted in said bore, an enlarged head on the lower part of the operating rod, grappling hooks pivoted in said slots and links pivotally connecting said hook and said operating rod, the enlarged part of said bore being adapted to 20 receive the enlarged head of said operating rod thereby limiting the movement of said rod.
- 25 2. A grappling device comprising a hub having a central bore and a plurality of vertical slots communicating with said bore, said bore being enlarged at its lower portion, an operating rod slidably mounted in said bore, an enlarged head on the lower end of said operating rod, grappling hooks pivoted in said slots, eyes on the inner faces 30 of said hooks adjacent their upper ends, a central eye secured to the enlarged head of said operating rod, links each having eyes formed in their ends, said eyes in said links 35 being adapted to be pivotally connected to 40

the eyes on the hooks and to the eye on the enlarged head of said operating rod whereby said hooks can be raised or lowered when said operating rod is manipulated.

3. A grappling device comprising a hub 45 having a central bore and a plurality of vertical and longitudinal slots in its lower portion, said bore being enlarged at its lower end, an operating rod slidably mounted in said bore, an enlarged head on the lower 50 part of the operating rod, grappling hooks pivoted in said slots, links pivotally connecting said hooks and said operating rod, the enlarged part of said bore being adapted 55 to receive the enlarged head of said operating rod thereby limiting the movement of said rod, and means for locking said hooks in a closed position.

4. A grappling device comprising a hub 60 having a central bore and a plurality of vertical and longitudinal slots in its lower portion, said bore being enlarged at its lower end, an operating rod slidably mounted in said bore, an enlarged head on the lower 65 part of the operating rod, grappling hooks pivoted in said slots, links pivotally connecting said hooks and said operating rod, the enlarged part of said bore being adapted 70 to receive the enlarged head of said operating rod thereby limiting the movement of said rod and a ring slidably mounted on said hub and adapted to slide over said vertical and longitudinal slots thereby preventing 75 said hooks from being raised.

In testimony whereof I affix my signature in presence of two witnesses.

JOHN E. GOLDEN.
